UNITED STATES PATENT OFFICE.

ADOLFO DE CLAIRMONT, OF TOLEDO, OHIO.

AIR-VALVE CONTROL FOR CARBURETERS.

1,116,673.

Specification of Letters Patent.

Patented Nov. 10, 1914.

Application filed June 28, 1913. Serial No. 776,219.

To all whom it may concern:

Be it known that I, ADOLFO DE CLAIRMONT, citizen of the United States, residing at Toledo, in the county of Lucas and State of Ohio, have invented certain new and useful Improvements in Air-Valve Control for Carbureters, of which the following is a specification.

My invention relates to new and useful improvements in carbureters and more particularly to means for automatically controlling the supply of auxiliary air to the carbureter, the primary object of my invention being the provision of a spring held auxiliary air valve mechanism so arranged that the springs controlling the opening of the valve may be adjusted to vary their tension in such a manner that the valve will automatically admit the passage of the proper proportionate amount of air to the carbureter, irrespective of the speed at which the engine is running and consequently of the amount of gasoline admitted. Heretofore auxiliary air valves of the above described type have been employed in which the opening of the valve is controlled by two springs, a low speed spring and a high speed spring, the former being the weaker and being the one which normally holds the valve closed and which controls the amount to which the valve shall open when running at low speed and the latter being arranged to be taken up after the valve is partially opened to control its further opening when the engine is running at high speed. In air valve constructions of the above character means have been provided for adjusting the tension of the low speed spring to permit the valve to initially open at any desired speed. No provision has, however, ever been made for varying the tension of the high speed spring to provide an adjustment by which the opening of the air valve at high engine speeds may be controlled.

Specifically then, the chief object of my present invention is the provision of means for varying the tension of this high speed spring without in any way affecting its usual operation or interfering with its action as a take up spring.

A still further object of my invention is to provide, in connection with the above adjustable controlling mechanism for the auxiliary air valve, means for supplying heated air to the port of the auxiliary air valve

from an air jacket about the exhaust manifold of the engine, the muffler or other suitable heated part of the engine structure. And a still further object of my invention is to provide a controlling mechanism and heated air supply system which may be employed upon carbureters having an auxiliary spray nozzle valve arranged to be opened and closed by the movement of the auxiliary air valve without in any way affecting the actuation of said spray nozzle valve by the air valve.

With these and other objects in view, my invention will be more fully described, illustrated in the accompanying drawings, and then specifically pointed out in the claims which are attached to and form a part of this application.

In the drawings: Figure 1 is a fragmentary elevational view of a conventional form of carbureter, showing my improvement applied thereto, portions being shown in section to more clearly show the construction and relation of the various parts; Fig. 2 is a similar view illustrating the employment of my controlling mechanism with a slightly different form of carbureter. Fig. 3 is a detail sectional view, illustrating a modified form of valve stem structure.

Corresponding and like parts are referred to in the following description and indicated in all the views of the drawings by the same reference characters.

In order to clearly disclose the construction and operation of my improved controlling mechanism for auxiliary air valves of carbureters I have illustrated the same in connection with two well known types of carbureters, one of which, in addition to the auxiliary air supply valve, is provided with an auxiliary gasoline nozzle and the other of which is identical with the former with the exception that it has but one gasoline nozzle, namely, the usual primary nozzle. It will be understood, however, that my improved controlling mechanism may be employed, with slight structural changes within the scope of a mechanic or designer skilled in the art, with many forms and types of carbureters other than those here shown.

Referring first to the carbureter shown in Fig. 1 of the drawings, 10 indicates the main body of the carbureter, the same being shown in elevation as the construction and arrangement of the primary spray nozzle, carburet-

ing and mixing chambers and other parts contained therein are of a conventional and well known type needing no illustration. The body or casing 10 is extended at one side as at 11 to provide a casing for an auxiliary air supply valve, this casing being hollow to provide a chamber 12 communicating with the mixing chamber of the carbureter through a passage 13 into which extends the secondary or auxiliary spray nozzle 14. The opening of this spray nozzle is controlled by a needle valve 15 normally held in closed position by a spring 16 and having a valve stem 17 extending through the top of the casing 11 and terminating in a head 18. This spray nozzle, together with its controlling valve, is of common type and no further description of the same is deemed necessary.

The upper wall of the valve casing 11 is ported in the usual way to permit the passage of air into the carbureter, the port being normally closed by an auxiliary air valve 19 mounted upon a valve stem 20 which extends by its ends through the upper and lower walls of the casing 11. The lower wall of the casing 11 is provided with a relatively large opening through which the valve stem passes, this opening being surrounded by an internally threaded nipple 21. A sleeve 22 surrounds the nipple, being free for turning movement thereabout and secured within this sleeve and against movement independent thereof, is an adjusting plug 23, the upper end of which is threaded to engage the threads of the nipple. A helical spring 24 surrounds the valve stem 20 bearing by one end against the plug 23 and by its other end against the valve 19 to normally hold the latter in elevated position against its seat and so prevent the entry of air. It will be readily apparent that the sleeve 22 may be turned manually in either direction to raise or lower the plug 23 and so vary the tension of the spring 24 and control the opening of the valve 19. In order to lock the sleeve in adjusted position, the casing 11 is provided with a downwardly depending lug 25 carrying a spring pressed locking pin 26, the free end of which is adapted to seat in one or another of a plurality of longitudinally extending grooves 27 formed in the peripheral face of the sleeve. The upper wall of the casing 11 is provided about the port with an upstanding, circular flange 28 and with spaced perforated ears 29 between which is pivoted a lever 30. One end of this lever is bifurcated to form spaced ears 31 engaging one upon either side of the valve stem 20, while the opposite end is similarly bifurcated to form spaced ears 32 extending one upon either side of the valve stem 17, the said lever 30 being so mounted that when the auxiliary spray nozzle valve

15 is completely closed the head 18 of the valve stem rests upon the lever which then occupies the position shown in the drawings.

A casing 33 is seated by its lower end within the flange 28 of the casing 11 and consequently surrounding the auxiliary air port and valve and formed integrally within the upper end of this casing or secured thereto in any suitable manner, is a pipe 34 which leads from any suitable source of heated air supply such as an air jacket about the exhaust manifold of the engine or about the muffler. This casing 33 is provided intermediate its length with a pair of transversely extending spaced spiders 35 and 36, both being provided with a relatively large central opening. One wall of the casing 33 is provided with an opening which is normally closed by a hinged door 37, this opening extending from a point considerably above the upper spider 36 to a point slightly below the lower spider 35. It will be apparent that when the engine is running at sufficient speed to open the auxiliary air valve 19, air will be drawn in through the pipe 34 and casing 33 through the air valve and so to the mixing chamber of the carbureter.

The opening formed centrally in the spider 35 is threaded to receive the threaded portion of a cylindrical sleeve 38 which is open at its upper end and closed at its lower end as at 39, the lower end of the sleeve being provided with a radially extending peripheral flange 40, the face of which is milled to permit ready manual turning of the sleeve to raise and lower the same through the spider 35. A second sleeve 41 has its open lower end telescopically mounted in the open upper end of the first sleeve and has its closed upper end 42 normally held against the lower face of the spider 36 by a helical spring 43 mounted within the sleeves 38 and 41 and bearing by its ends against the closed ends 39 and 42 thereof. Said closed ends are provided with aligned openings for the passage of a supplemental valve stem 44, the lower end of which is enlarged to form a head 45. This head is provided with a socket to receive the upper end of the valve stem 20, the valve stem and supplemental stem being connected by a threaded pin or other suitable fastening device 46. The upper end of the supplemental valve stem 44 extends through the opening in the closed end 42 of the sleeve 41 and through the central opening of the spider 36, being threaded to receive a milled adjusting nut 47. The outer face of the sleeve 38 is provided with a plurality of longitudinally extending grooves 48 to seat the rounded end of a spring pressed pin 49 which is mounted through the wall of the casing 33 and which therefore serves to lock the sleeve 38 in

adjusted position. The connection between the valve stem 20 and supplemental stem 44 is such that the latter may be adjusted with respect to the former to vary the extent to which the former must move before the head 45 of the latter will engage the lever 30 to open the auxiliary nozzle valve. If desired, it will of course be apparent that the valve stems 20 and 44 may be replaced by a single valve stem, as shown in Fig. 3, in which instance the valve stem thus provided will be threaded at a point immediately below its passage through the closed lower end of the sleeve 38 to receive an adjusting nut which may be moved toward and away from the lever 30 to accomplish the same adjustment accomplished by the socketed head 45 and pin 46.

The operation of the above described carbureter, particularly that of my improved auxiliary air valve controlling mechanism, will be readily understood from the drawings and but slight description of the same is necessary. When the engine is running at low speed, sufficient air will be drawn in through the main or primary air supply port of the carbureter and the valve 19 and consequently the auxiliary spray nozzle valve 15 will both remain closed. As the speed of the engine increases however, air will be drawn in through the pipe 34 and casing 33 forcing the auxiliary air valve 19 open a slight distance against the action of the spring 24 which is the low speed spring of the auxiliary air valve. The gradual further increase in engine speed will still further open the valve 19 until the head 45 of the supplemental valve stem depresses the lever 30 to open the auxiliary spray nozzle valve 15 and thus admit an additional amount of gasolene, this gasolene, together with the auxiliary air admitted through the valve 19, passing directly into the mixing chamber of the carbureter. As soon as the engine begins to run at high speed the valve 19 will be open to such an extent that the adjusting nut 47 will engage against the closed upper end 42 of the sleeve 41. From then on, all further opening of the valve 19 is not only accomplished against the action of the spring 24 but also against the action of the spring 43. As both the springs 24 and 43 are capable of independent adjustment, it will be apparent that the parts may be so adjusted that the auxiliary air valve 19 will be opened to any desired extent at any desired speed of the engine. Because of this the auxiliary air valve, when once properly adjusted, will be automatic in its action supplying exactly the right proportion of auxiliary air to the carbureter to combine with the amount of gasolene admitted at the speed at which the engine is running to provide a perfect combustible mixture for

the engine at such speed. By movement of the adjusting nut 47, the amount which the auxiliary air valve 19 must open before the high speed spring 43 is brought into play may be regulated, while by turning 70 the sleeve 38 the tension of the spring 43 may be adjusted. It will of course be apparent that both of these adjustments may be readily and conveniently made by opening the door 37. 75

The construction shown in Fig. 2 of the drawings is identical with that shown in Fig. 1, with the exception that the auxiliary spray nozzle and its valve are omitted, together with the lever 30. It will therefore 80 be apparent that with this form of construction, if the valve stem 20 and supplemental stem 44 are replaced by a single valve stem, such valve stem need not be threaded intermediate its length to receive the adjusting 85 nut mentioned in the description of the construction shown in Fig. 1. In this instance, as in the former, the auxiliary air passing through the valve 19 is admitted directly to the mixing chamber of the carbureter. 90

Having thus described the invention, what is claimed as new is:

1. A carbureter including a single auxiliary air valve, a low speed spring controlling the opening of said valve, a high speed 95 spring brought into play after partial opening of said valve to control its further opening, and means for adjusting the tension of the high speed spring.

2. A carbureter including a single auxiliary air valve, low and high speed springs controlling the opening of said valve, the latter becoming operative only after partial opening of the valve, and means for independently adjusting the tension of said 105 springs.

3. A carbureter including an auxiliary air valve, a spring normally holding said valve in closed position, means for adjusting the tension of said spring, a second spring arranged to become operative only when the valve has been partially opened against the first spring to act against further opening, and means for adjusting the tension of said second spring. 110

4. The combination with a carbureter having an auxiliary air valve casing and air valve mounted therein, the air valve having a stem extending through the top of the casing, means for normally and yieldably holding the valve against its seat, a spring engaging about the valve stem and normally having no effect on the valve, means for tensioning the spring, and means carried by the stem for engagement with the spring 120 only after partial opening of the valve.

5. The combination with a carbureter having an auxiliary air valve casing, a valve mounted in the casing, a spring engaging the valve to normally hold the same closed, 130

of a valve stem carried by the valve and extending through the casing, spiders supported in spaced relation above the casing, a sleeve threaded through one of the spiders 5 and closed at one end, a second sleeve bearing by a closed end against the other spider and having an open end extending within the open end of the first, a spring surrounding the valve stem and located within the 10 sleeves, being compressed between the closed ends thereof, and a nut adjustably threaded upon the valve stem for engagement against the second sleeve upon partial opening of the valve.

15 6. The combination with a carbureter having an auxiliary air valve and an auxiliary spray nozzle valve, of a valve stem for the auxiliary air valve, means for normally holding the auxiliary air valve stem to hold 20 its valve in closed position, means operable by the partial opening of the auxiliary air valve for opening the spray nozzle valve, a spring co-acting with the valve stem after partial opening of the valve, and means for 25 adjusting the tension of said spring.

15 7. The combination with a carbureter having an auxiliary air valve and an auxiliary spray nozzle valve, of a valve stem for the

auxiliary air valve, means for normally holding the auxiliary air valve stem to hold 30 its valve in closed position, means operable by the partial opening of the auxiliary air valve for opening the spray nozzle valve, a spring co-acting with the valve stem after 35 partial opening of the valve, means for adjusting the tension of said spring, and means for varying the extent to which the air valve may open before said spring becomes active.

8. The combination with a carbureter having 40 an auxiliary air valve and a low speed spring controlling the opening of the valve, or a valve stem, telescopic sleeves mounted about the valve stem, the valve stem being movable therethrough, a helical spring 45 compressed between the ends of said sleeves, means for adjusting one sleeve with respect to the other to tension the spring, and means adjustable upon the valve stem for engagement with one of said sleeves.

In testimony whereof I affix my signature in presence of two witnesses.
